UNITED STATES PATENT OFFICE.

WILLIAM C. DODDRIDGE, OF NEW MADRID, MISSOURI.

HEATING-DRUM.

SPECIFICATION forming part of Letters Patent No. 223,715, dated January 20, 1880.

Application filed February 8, 1879.

To all whom it may concern:

Be it known that I, WM. C. DODDRIDGE, of the city and county of New Madrid, and State of Missouri, have invented a new and 5 Improved Heating-Drum; and I do hereby declare that the following is a full, clear, and exact description of the same.

The object of my invention is to provide an improved heating device of the kind forming 10 an attachment or appendage of a stove or furnace pipe, and commonly employed as a substitute for a stove or grate in apartments contiguous to that in which is situated the stove or furnace with which such pipe connects.

The construction of the drum is as herein-after described, the same being shown in accompanying drawings, forming part of this specification, in which—

20 Figure 1 is a vertical central section of the drum, and Fig. 2 a vertical section on line x x of Fig. 1. Fig. 3 is a vertical central section of a drum having a modified construction, and Fig. 4 is a side view of the same.

25 The body of the drum is formed of the three superposed parts or sections A B C, which are oval in cross section and graduated in size, the middle part, B, being smaller than the lower part, A, and larger than the upper 30 part, C.

Referring particularly to Figs. 1 and 2, the lower and upper parts or sections, A C, have collars a b at top and bottom to adapt them for connection with stove-pipes. A damper, 35 c , is pivoted in the lower collar, b . The lower part, A, has a series of vertical tubes, D, arranged near the shell or casing, and open at top and bottom, so that air has free passage through them. In said Figs. 1 and 2 a per- 40 forated detachable oval cap or collar, E, is shown placed upon the laterally-projecting top portion of part A, and surrounding the base of section B. Said cap serves partly as an ornamental appendage of the drum; but 45 its practical function is to break up the currents of heated air rising from tubes D, and it thus aids in distributing the heat in the apartment in which the drum is located.

In the interior of the drum are placed four 50 concavo-convex plates, which are arranged horizontally, and serve to deflect the current of heated air, smoke, and gases of combustion entering through the stove-pipe at a . The small deflector F is placed directly over the

opening at b . The largest deflectors, G H, are 55 suspended by chains in the part A—one near the top and the other near the bottom, above deflector F. The fourth deflector, I, is arranged in the upper portion of the middle section, B.

The current of heated products of combustion entering at b strike against the under side of deflector F, and are thus diverted and directed beneath the lower deflector, G, which in turn directs it laterally against the tubes 65 D and the adjacent side of the drum. The latter (tubes and side of the drum) thus become heated, so that currents of heated air are established through the tubes, as will be readily understood.

70 The deflector H supplements the function of its companion G, and the upper deflector, I, again diverts the current laterally. Thus the heated products of combustion are caused to project laterally against and take their 75 general course alongside the walls of the drum, so that the heat is utilized as fully as practicable without serious obstruction of the draft.

70 The modification shown in Figs. 3 and 4 80 differs from the drum shown in Figs. 1 and 2 in these particulars, to wit: A stove, K, is placed in the base-section A, and the deflector G is dispensed with, and an imperforate cap, E', is substituted for the perforated one 85 E. The cap E' is provided with a collar at each end for attachment of pipes L, which join with a pipe, M, that conducts to another apartment the heated air rising from tubes D. The employment of the stove K renders it 90 practicable to derive a sufficient supply of heated air for this purpose.

I do not claim, broadly, the employment of deflectors or heat-distributors in a stove, heater, or drum, nor providing such drum or 95 heater with open-ended tubes for passage of heated air.

What I do claim is—

The improved heating-drum consisting of the body A B C, provided with top and bottom openings, and having open-ended tubes D, arranged as specified, and the deflectors 100 arranged horizontally, all as shown and described.

WILLIAM C. DODDRIDGE.
